RENEWABLE CARTRIDGE FUSE

Charles J. Haas, New York, N. Y.

Application March 21, 1941, Serial No. 384,498

5 Claims. (Cl. 200—131)

This invention relates to renewable cartridge fuses, and is more particularly directed toward renewable cartridge fuses of the ferrule type.

The present invention contemplates the provision of renewable fuses which are susceptible of inexpensive manufacture, which are suitable for repeated use under severe conditions and wherein it is easy to renew the fuse link.

The accompanying drawing shows, for purposes of illustrating the present invention, two of the many embodiments in which the invention may take form, it being understood that the drawing is illustrative of the invention rather than limiting the same.

In the drawing:

Figure 1 is a longitudinal sectional view through a cartridge fuse taken on the line 1—1 of Figure 2;

Figure 2 is a longitudinal sectional view on the line 2—2 of Figure 1; and

Figures 3 and 4 are cross sectional views on the lines 3—3 and 4—4, respectively, of Figure 1.

The outer casing of the fuse is indicated at 10. While this casing may be made of any suitable insulating material it is preferably made of transparent insulating material in order that the interior of the fuse may be seen. This feature of construction forms the subject matter of my co-pending application Serial No. 384,497 filed concurrently herewith.

The casing or sleeve 10 receives an insulating member 11 which may also be made of transparent material. This insulating member has diametrically opposite grooves 12, 12 at the ends and a longitudinally extending slot 13 which communicates with these grooves. This slot extends all the way across the rod forming the insert 11 to leave two outer connecting members 14, as will be apparent from the section of Figure 4. A fuse link 15 is received in the cut-out portions of the rod 11 and has its ends 16 bent over the ends of the rod 11, as will be apparent from the drawing. The ends of the fuse link are apertured and the ends of the rod 11 are threaded as indicated at 17, 17.

End members 18, 18 in the form of sheet metal end caps 19 and threaded studs 20 are provided. In assembling the fuse one end of the fuse link is bent at the proper point to bring its aperture in alignment with the threaded opening in the end of the inner rod, and an end member is threaded into place so as to securely clamp the end of the fuse link between the shoulder on the stud and the end of the rod. The other end of the fuse link is then bent around the end of the

inner rod. The outer sleeve 10 is then passed about the inner rod and fuse link and the other end member threaded in place. The lengths of the parts are such that the clamping action takes place between the shoulders on the studs and the ends of the insulating insert. The insulating sleeve 10 is slightly smaller than the inside diameter of the ferrule or end cap 19 and is slightly shorter than the distance between these end caps so that gases generated when the fuse blows will find a ready passage through the grooves and spaces referred to.

It is obvious that the invention may be embodied in many forms and constructions within the scope of the claims and I wish it to be understood that the particular forms shown are but a few of the many forms. Various modifications and changes being possible, I do not otherwise limit myself in any way with respect thereto.

20 What is claimed is:

1. A cartridge fuse comprising an insulating sleeve, end members including metal end caps fitted about the ends of the sleeve and having axially disposed, inwardly extending threaded studs, an insulating member received in the sleeve, and a fuse link having apertured ends bent against the ends of the insulating member and through which the threaded studs extend, the end members having shoulders bearing on the link ends when the studs are threaded tightly in place.

2. A fuse such as claimed in claim 1, wherein the insulating member has a longitudinally extending chamber through which the fuse link extends diagonally.

3. A fuse such as claimed in claim 1, wherein the insulating member is provided with longitudinally extending grooves extending to the ends and has a longitudinally extending fuse link receiving chamber communicating with the grooves so that gases generated on blowing of the fuse link may escape.

4. A renewable fuse having an insulating tubular casing, a removable end cap carrying an axially extending screw, an insulating rod in the casing and tapped to receive the screws, and a fuse link whose ends are clamped against the ends of the rod by the screws, the rod being cut away to provide in conjunction with the casing an explosion chamber through which the fuse link passes.

5. In combination, an insulating carrier for a fuse link comprising a length of cylindrical rod having axially disposed threaded holes in the ends, diametrically opposite grooves near the

ends and a slot extending from the grooves at one end to the grooves at the other end and cutting the central portion of the rod so as to leave two interconnecting members, a fuse link extending through the grooves and cut-out central portion of the rod and having apertured ends opposite the threaded holes, metal caps having peripheral portions spaced from the outside

5 of the rod and screws passing through the link ends and threaded tightly into the holes so that the caps and link ends are in intimate electrical contact, and an outer insulating sleeve about the rod and having its ends loosely received inside the caps.

CHARLES J. HAAS.
